UNITED STATES PATENT OFFICE.

GRAVES R. MAUPIN, OF MOBERLY, MISSOURI, ASSIGNOR TO THE J. FAESSLER MANUFACTURING COMPANY, A COPARTNERSHIP COMPOSED OF JOHN W. FAESSLER, CHRISTINIA FAESSLER, LOUIS E. FAESSLER, AND GRAVES R. MAUPIN, ALL OF MOBERLY, MISSOURI.

METHOD OF AND APPARATUS FOR FINISHING CYLINDRICAL BEARING SURFACES.

Application filed February 1, 1926. Serial No. 85,149.

My invention relates to improvements in method of and apparatus for finishing cylindrical bearing surfaces, and has for its primary object the method of finishing a cylindrical bearing surface whereby the bearing surface is given an extremely smooth finish and also toughened during the finishing operation.

A further object is the finishing of a cylindrical bearing surface by applying a rolling pressure thereto thus compressing the surface and toughening the same.

A further object is to construct an apparatus for finishing cylindrical bearing surfaces in which a plurality of expanding rollers are employed which give the surface of the bearing treated thereby a smooth mirror-like finish.

A still further object is to construct an apparatus which will not only finish cylindrical bearing surfaces but which can also be used for tightening bushings throughout their length in all types of cylinders and without the use of hydraulic presses or heating and shrinking the cylinder on to the bushing as is at the present time done. One of the important features resulting from my method and apparatus is the rolling of a true smooth wearing surface and by so doing compress and toughen this wearing surface so that all grinding or honing of the surface is eliminated. Another feature is that a cylinder or a cylindrical bearing surface so finished does not have to be worked in as is necessary where cylinders have been ground or honed.

A still further advantage of my device is that a bearing surface treated by my apparatus and method is free from all particles of abrasive, which is not the case where cylinders are ground or honed, for the reason that small particles of abrasive are forced into the pores of the metal and there is always a possibility of the bearings becoming scored from such particles.

In the drawings:

Fig. 1 is a sectional view of a cylinder showing my device in position in the act of rolling in a bushing;

Fig. 2 is a longitudinal section of a cylinder showing a modified form of my device therein in which the bearing surface and the cylinder itself is being treated;

Fig. 3 is an end view of Fig. 1 looking in the direction of the arrow 3;

Fig. 4 is a longitudinal section of the apparatus illustrated in Fig. 1;

Fig. 5 is an enlarged face view of the sliding collar employed;

Fig. 6 is a longitudinal section of the apparatus employed in Fig. 2;

Fig. 7 is an enlarged view of one of the expander rollers;

Fig. 8 is a fragmental diagrammatic section showing the molecular structure of a piece of metal before being treated by my method; and

Fig. 9 is a similar view showing the metal after being treated.

In the construction of my device, 10 represents a cylinder which has been bored out and in which a bushing 11 has been inserted. This bushing is preferably cast iron, brass or bronze as found necessary as my device can be used in engine cylinders, pump cylinders, or in fact in any place where a cylindrical bearing surface is required.

My apparatus as illustrated in Fig. 1 is constructed in the following manner:

12 represents a cage which has a plurality of slots or openings 13 formed in its periphery. These openings are preferably at an angle to the longitudinal axis of the cage and each opening has located therein a roller 14. These rollers when in position will have 85 their longitudinal axis at an angle to the longitudinal axis of the cage. The cage is provided with a central bore 15 in which is located an expanding head 16. This expanding head contacts with the face of the 90 rollers 14. The expanding head is tapered so that as it is fed forward, it will force the rollers outward and cause them to bear against the cylindrical surface in such a manner that the rollers will bear throughout 95 their length against the cylindrical surface and also against the expanding head thereby preventing the rolling of any ridges in the cylindrical surface. The expanding head 16 is provided with a central bore 17 which has 100 a key-way 18 formed therein in which the key 19 is located. The key 19 is also seated in the reduced portion 20 of the mandrel 21. By this means the head 16 and mandrel 21 rotate simultaneously. The head 16 is held 105 on the mandrel by means of the nut 22.

The rear of the cage 12 is provided with a sleeve 23 in which a thrust bearing 24 is seated. The mandrel 21 is provided with a key-way 25 and screw threads 26. Mounted 5 on the mandrel 21 is a sliding collar 27 which is provided with a key 28. This key is seated in the key-way 25 and in this manner the collar 27 is held against any rotation on the mandrel but is free to slide longitudinally. Mounted on the screw threaded portion of the mandrel is a collar 29 which is screw threaded so that it can move longitudinally by being turned. The collar 29 is provided with a recess in which is mounted 10 a block 30. This block is provided with screw threads as illustrated in Fig. 4 and is designed to be pressed against the mandrel by means of a set screw 31. In this manner the collar 29 can be locked on the mandrel 15 without disturbing or mutilating the screw threads in any way. The purpose of the collars 27 and 29 is to form a depth gauge for the expanding head and prevent it from pushing the rollers outward beyond a predetermined distance.

The mandrel 21 is also provided with openings 32 and 33 arranged at right angles to each other through which a bar can be inserted for rotating the mandrel and with a 20 square end 34 by means of which the mandrel can be rotated either by a wrench or handle or by means of a power-driven device.

In Fig. 6 I have shown a slightly modified form of apparatus in which the cage is provided with a sleeve 36 formed integral therewith. This sleeve is screw threaded as at 37 and has placed thereover a screw threaded sleeve 38 and a lock nut 39. In this construction the mandrel 40 is not provided 25 with screw threads but has a collar 41 formed integral therewith and adjacent the end opposite the expander head 42. The expander head 42 is held on the mandrel by means of the key 43 and nut 44. Adjacent the collar 45 41 is a square portion 45 by means of which the mandrel can be rotated, and interposed between the collar 41 and sleeve 38 is a thrust washer 46. This washer is loosely mounted on the mandrel and is designed to 50 receive the thrust from the collar 41 and eliminate twisting action on the sleeve 38 as much as possible. The lock nut 39 is for the purpose of preventing the accidental movement on the sleeve after it has once been 55 adjusted. The sleeve 38 and collars 41 and 46 act as a depth gauge for preventing the rollers 47, which are of the same construction as the rollers 14, from expanding too far.

60 The operation of my device is as follows: I will first explain the method of finishing the interior of a cylinder. The cylinder after coming from the foundry is first placed in a boring mill and bored out to approximately its finished size. After this there

will be tool marks on the inside of the cylinder, which will leave the surface too rough to be used without further finish. I then insert my apparatus in the cylinder and push the mandrel and expander head 70 forward so that the rollers will bear against the surface of the cylinder. The gauge is now set a slight distance away from the thrust collar and the mandrel rotated. This also rotates the expander head and due to 75 the inclination of the axis of the rollers to the axis of the cage, the mandrel will feed forward, expanding the rollers and causing them to bind tightly against the interior of the cylinder. Continued rotation of the 80 mandrel causes the rollers to rotate and in so doing causes the entire apparatus to move longitudinally through the cylinder, compressing the metal and ironing out all of the tool marks. After the apparatus has 85 been passed through the cylinder, it is withdrawn, the gauge moved back a slight distance, and the operation repeated until the proper size of bore has been reached. It is 90 to be understood, of course, that the bore 95 of the cylinder is approximately the finished size because by my method I do not remove any material from the bearing surface but only compress or condense the surface. During this operation of rolling, it is, of course, necessary that the interior surface of the cylinder be lubricated, and I have found that during the operation a certain amount of lubricant is forced into the pores of the metal and retained thereby. This also 100 makes it easier when breaking in a new cylinder because I have found that a cylinder treated by my method and afterward washed out and dried so that no trace of lubricant remains therein, upon being heated 105 oozed lubricant into the cylinder from the cylinder walls, thus assisting greatly in the breaking in operation and eliminating the excessive use of oil during such operation.

When my device is used on cylinders which have been bushed, it is not necessary to force the bushing in by means of a hydraulic press, or in cases of large cylinders to heat the same so that they will expand 110 sufficiently to permit the insertion of the bushing and then shrink them on the bushing as the cylinder is bored out to allow for the insertion of the bushing and the exterior diameter of the bushing made so that it will be a drive fit. A fit of this kind 115 would be too loose for actual practice but by using my apparatus, not alone is the interior surface of the bushing condensed and toughened but the entire bushing is expanded and firmly seated and held within the cylinder. This makes my device especially useful for all types of engine and pump cylinders, and especially for locomotives as in some of the larger locomotives it 120 is necessary to remove the cylinders entirely 125

and after boring out the cylinders heat them and shrink them on to the bushing. This makes an expensive operation and if the bushing is too large, there is always a possible chance of cracking the cylinder.

head 16 is eliminated and the forward end of the mandrel 21 is tapered, this tapered portion acting in the same manner as the expanding head, that is as it is fed into the cage, it will force the rollers outward causing them to engage against the surface to be treated. 70

I have also discovered that by the use of my apparatus a true bore can be obtained. This, it is virtually impossible to obtain by means of a grinding machine on account of the wear of the abrasive so that one end of the cylinder will always be a trifle smaller than the other and therefore a perfect bearing or fit can not be obtained. This is especially true of engine and pump cylinders 10

75

where the piston travels backward and forward. A cylinder with a taper as just described is extremely hard on the piston rings because they are constantly being compressed and expanded, which crystallizes 15

them and causes them to wear out much more rapidly than if a true cylindrical surface were obtained. 20

It will be obvious from the foregoing description of the operation of my device that the same will feed itself automatically 75

through the bushing to be finished and is not dependent on any extraneous pressure exerted along its longitudinal axis to accomplish this movement. 80

It will also be further noted that with my device it is not necessary to heat the bushing to be finished but that my method is directed solely to a cold finished process. 85

Having fully described my invention, what I claim is:— 85

1. The method of finishing a cylindrical bearing surface which consists in applying to said surface a sufficient pressure by a rolling contact to compress and smooth the wearing surface of said bearing, and causing said 90 rolling contact to move said pressure longitudinally of the surface.

2. The method of finishing a cylindrical bearing surface which consists in applying to said surface a gradually increasing rolling pressure, and simultaneously moving said pressure longitudinally along said surface 95 without the use of extraneous feeding means whereby the texture of said bearing adjacent the surface is rendered more compact and 100 dense and the surface toughened.

3. The method of finishing a cylindrical bearing surface which consists in applying pressure to said surface at equally spaced 105 apart circumferential points, and then moving said points of pressure circumferentially and longitudinally automatically throughout the length of the surface.

4. An apparatus of the class described 110 comprising a cage, expanding rollers mounted in said cage said rollers having their longitudinal axis at an angle to the longitudinal axis of the cage and adapted to be projected beyond the periphery thereof, 115 an expanding head mounted in said cage and contacting with said rollers, a mandrel secured to said expanding head, means for securing said mandrel and head together against independent rotation, adjustable means for limiting the forward movement 120 of said expanding head for regulating the projection of said rollers, and means on one end of said mandrel and adapted to receive a means for rotating said mandrel. 125

5. An apparatus of the class described 130 comprising a cage, expanding rollers mounted in said cage and having their longitudinal axis at an angle to the longitudinal axis of said cage, a tapered expanding head mounted in said cage and contacting with

130

While I have described my device as being used for engine and pump cylinders, it can be used for any kind of cylindrical bearings and a bearing so treated does not have to be scraped and fitted. This makes my device especially adapted for locomotive main and side connecting rod bushings, and all sorts of cylindrical bearing bushings, as well as cylindrical bearings and cylinders of all kinds without bushings as the bearing surface of the latter can be readily treated and condensed and toughened by my process. My device can also be used to advantage in repairing scored automobile cylinders in which grooves have been cut deep enough to require filling in by metal as the filling can be packed in much more tightly and finished with less labor and time than is now required.

My device may be made of any size and employ any number of rollers from three on up, depending on the size of the apparatus and the class of work for which it is intended. In Fig. 8 I have shown a fragmental section of a portion of a cylinder before the same has been treated, as it would appear when enlarged many diameters and showing the molecular structure. In this it will be plainly seen that the molecules are evenly distributed throughout the piece whereas in Fig. 9 the molecules along the treated surface are very much condensed. This condensing not only makes the surface smooth and eliminates pores but also has a tendency to toughen the metal thereby increasing its life and preventing it from wearing away as rapidly as if the natural surface was exposed to wear.

It is to be understood, of course, that the rollers 14 and the expanding head 16 are both made of hardened tool steel. It is further to be understood that in rolling small cylindrical bearing surfaces the expanding

- said rollers, a mandrel secured to said expanding head and projecting rearwardly therefrom and from said cage, said mandrel and expanding head being secured together 5 against independent rotation, adjustable means mounted on said mandrel and adapted to contact with the cage for limiting the forward movement of the expander head within said cage, the rear end of the mandrel arranged to receive a means whereby the mandrel can be rotated.
6. An apparatus of the class described comprising a cage, a sleeve integral with said cage, rollers located in said cage and adapted to have their periphery projected beyond the periphery of the cage, the longitudinal axis of said rollers being at an angle to the longitudinal axis of the cage whereby said cage is automatically moved forward 10 when rotated, a mandrel movable centrally through said sleeve and projecting into said cage, a tapered expanding head mounted on one end of said mandrel, means for securing said mandrel and expanding head together 15 so that the same will rotate simultaneously, a collar formed integral with said mandrel adjacent its rear end, a second sleeve adjustably mounted on said first mentioned sleeve and adapted for contact with said collar for 20 limiting the travel of said mandrel through said first mentioned sleeve, the mandrel being provided adjacent the collar with means to receive a device for rotating the mandrel.
- 25 7. The method of cold finishing a cylindrical bearing surface which consists in subjecting said surface successively to a gradually increasing continuous rolling pressure at circumferentially spaced apart points whereby the molecular structure of the bearing near the wearing surface is rendered more compact and dense and the 30 surface given a smooth finish.
- 35 8. The method of cold finishing a cylindrical bearing surface which consists in subjecting said surface to an outwardly directed circumferentially and an automatically longitudinal moving rolling pressure of sufficient intensity to render said surface smooth and the texture of said bearing adjacent said surface more dense and compact.
- 40 9. The method of finishing a cylindrical bearing surface which consists in applying a lubricant to said surface, subjecting said surface to a longitudinally traveling out- 45 wardly directed circumferentially moving pressure at circumferentially spaced apart points throughout its length, and repeating the application of said pressure until the texture of the bearing adjacent said surface has been rendered more dense and a smooth bearing surface of a predetermined diameter obtained.
- 50 10. The method of finishing a cylindrical bearing surface which consists in applying to said surface at circumferentially spaced apart points an outwardly directed pressure sufficient to compress and smooth the wearing surface of said bearing, moving said pressure longitudinally of the bearing while it is being applied and simultaneously therewith enlarging the outside diameter of said bearing.
- 55 11. The method of finishing the inside of bushings and similar cylindrical bearings, which consists in subjecting the surface to be finished to a longitudinally extending radially directed outward rolling pressure, moving said pressure circumferentially and longitudinally of said surface and simultaneously therewith increasing the outside diameter of said bushing.
- 60 12. The method of finishing the inside surface of cylindrical bushings, which consists in placing said bushing in a cylindrical bore of slightly greater diameter than the outside of said bushing, subjecting the interior of the bushing to a longitudinally extending radially directed outward rolling pressure moving longitudinally and circumferentially through said bushing whereby the interior surface of said bushing is smoothed and condensed and said bushing simultaneously expanded and tightly seated within the cylindrical bore.
- 65 13. The method of finishing and toughening the internal wearing surface of cylindrical bearings, which consists in subjecting said surface progressively throughout its length to a slow longitudinally moving outwardly directed rolling pressure simultaneously exerted at circumferentially spaced apart points, and repeating said operation until the desired internal diameter is obtained whereby a smooth condensed wearing surface is obtained.
- 70 In testimony whereof I have affixed my signature.
- GRAVES R. MAUPIN.
